HENRY KENT-NORRIS, OF NEWBURY, ENGLAND, ASSIGNOR TO PLENTY & SON LIMITED, OF NEWBURY, ENGLAND.

GOVERNING MECHANISM FOR INTERNAL-COMBUSTION ENGINES.

Application filed October 11, 1920. Serial No. 416,220.

To all whom it may concern:

Be it known that I, HENRY KENT-NORRIS, a subject of the King of Great Britain, residing at Ashdown, Pyle Hill, Newbury, 5 Berkshire, England, have invented certain new and useful Improvements in and Connected with Governing Mechanism for Internal-Combustion Engines, of which the following is a specification.

10 This invention comprises improvements in and connected with governing mechanism for internal combustion engines. In these engines, and particularly in engines consuming liquid fuel, the governor operates to cut 15 out the fuel supply during one or more strokes and when the speed has been sufficiently reduced for the governor to cut in the supply again, it is a common thing for the explosion following to be of a violent 20 character. For example, during the idle stroke or strokes, the cylinder may become filled with pure air, and, when the governor cuts in, a full charge of liquid fuel is injected and, an efficient mixture being made, a 25 powerful explosion and impulse result from the ignition of this charge of mixture. An important object of the present invention is to prevent this violent explosion after a cut out period and thereby secure greater efficiency and more even running of the engine. 30 A further object is to render it possible to have a graduated resumption of the charging of the engine after a cut out period, if this should be desired. A still further object is 35 to reduce the amount of wear and tear on the governor mechanism, thereby prolonging its life and maintaining its efficiency. Finally an object of the invention is to adapt the improvements for the simultaneous cutting 40 out of two or more cylinders so that it is impossible for one cylinder to be cut out more often than another and uniformity in the loading and working conditions of the different cylinders is thereby ensured.

45 According to this invention, the improved governor mechanism comprises in combination a cam plate or lever device, maintained in an operative position by a spring and adapted to be moved by a governor device, 50 during abnormal speed conditions, to a position in which the cut off of the fuel supply is effected, and an automatic trip device adapted for simultaneously locking the cam plate or lever device in the operative posi-

tion against the action of the spring and 55 projecting itself into the normal path of the governor device, so that, upon a reduction of the speed to the normal, the trip device will be operated for releasing the cam plate or lever device and restoring the 60 fuel supply. In the normal inoperative position of the cam plate or lever device the trip device lies out of range of the governor device so that there is no unnecessary wear 65 and tear on these parts, and by a simple adjustment of the trip device it is possible to time the operation of the trip device so that any desired reduced charge may be supplied or admitted to the engine cylinder after a cut out stroke or period.

In order to enable this invention to be 70 readily understood, reference is made to the accompanying drawings, in which:—

Figure 1 is a side elevation of a governing mechanism constructed and arranged in accordance with this improvement and adapted for use with a single cylinder engine.

Figure 2 is a side elevation of a mechanism similar to that seen in Figure 1 but adapted for use with a two-cylinder engine.

Figure 3 is a side elevation illustrating a modification as adapted for use with a two-cylinder engine.

Fig. 4 is a diagrammatic view of an arrangement of governor device similar to 85 that shown in Figure 1, and

Fig. 5 is a diagrammatic side elevation of the same governor device showing its relation to the fuel pump and its driving mechanism.

In a suitable construction embodying these features, and as seen in Figure 1, an inertia governor device comprises a reciprocatory rod *a* having a rounded projection *b* or the like, which is maintained in contact with a slide surface *c c'* by a spring, not shown. The said surface comprises two rectilinear paths, one marked *c* and the other *c'* connected by an incline or step *d* disposed about midway along the slide path. The reciprocatory rod *a* carries a striker block *e* formed with an angular recess *e'* in its forward end, and an angle lever *f f'* is pivotally mounted so that one of its arms, namely the arm marked *f*, lies in the plane containing the path of travel of the block *e* and so that the extremity of this arm *f* lies just beyond the normal path of the block *e*. During normal

speed conditions, the rod *a* reciprocates and its projection traverses the slide path *c*, *d*, *c'* so that during each alternate stroke it ascends the incline or step *d* against the 5 action of the spring, but the speed of such ascent is not sufficient to throw the rod *a* outwards to such an extent that the block *e* will engage the arm *f* of the angle lever. When the speed becomes excessive, however, 10 the projection *b*, in making the ascent, throws the rod *a* out sufficiently for the block *e* to engage the arm *f* of the angle lever, whereby the latter is turned through a predetermined angle. The other arm *f'* 15 of the angle lever is adapted to engage an arm *g* on a spindle *h* upon which a cam disc or plate *j* is mounted, so that the engagement of the block *e* with the lever arm *f* effects a partial revolution of the cam disc 20 or plate *j*. The latter, when so turned, is adapted for operating a suitable valve *k* controlling the admission or supply of fuel to the engine. For example, the cam may 25 press open a bye-pass valve on an injection feed pump, so that the latter will fail to deliver a charge to the engine, or it may hold open the suction valve of the pump, so that the pump will fail to make a delivery owing to the suction being open during 30 the delivery stroke. The said partial revolution of the cam *j* is effected against the action of a spring, not shown, which constantly tends to maintain the cam plate *j* in the normal position, and the immediate 35 return of the cam plate to such normal position is prevented by means of a trip pawl *l* which takes into suitable teeth or recesses *m* formed in the periphery of the cam plate or disc *j*, this engagement of the pawl *l* being 40 suitably effected by means of a small spring plunger *n*. The pawl *l* forms one arm of a two-armed lever *l' l''* and the entry of the pawl *l* into one of the toothed recesses *m* permits the other arm *l'* of the lever to move forwardly towards the extremity of the reciprocating rod *a*. This arm of the lever is fitted with an adjustable set screw *p* designed to form an abutment or striking surface for the extremity of the 45 said rod *a*, and the set screw *p* is so adjusted that, in this forward position of the lever, the end of the set screw *p* projects into the path of the rod *a*, or into range for operation by the extremity of such rod. 50 When the speed falls again to the normal, therefore, the rod *a* makes a stroke, and its block *e* misses the angle lever arm *f*, but its extremity strikes the set screw *p* of the two-armed pawl lever *l' l''* thereby releasing the 55 pawl *l* from the toothed recesses *m* of the cam plate or disc *j*, and permitting the latter to be turned to its normal position by means of its spring. Thus the pump is restored to normal working conditions and is free to 60 supply the engine cylinder with an injection.

Let it be supposed, for the purposes of illustration, that the pump normally makes its injection during the last three millimetres of travel of the reciprocating rod *a*, then suppose that the screw *p* is adjusted so that, in the forward position of the lever arm *l'*, it overlaps the path of the rod *a* to the extent of two millimetres, it will be apparent that upon the striking of the trip pawl arm *l'* by the governor rod *a*, so that the pawl *l* 75 is released and the cam disc *j* is returned by its spring the pump will be restored to normal working so late in the stroke that it will not be able to deliver a full charge but that it will deliver only two-thirds or less 80 of the full charge. Naturally, if the screw *p* is adjusted towards the rod *a*, the release of the cam *j* will take place earlier and the amount of the charge will be greater than before. Therefore, after a cut-out period 85 or stroke, the first effective stroke of the engine is not made under the effort produced by a full charge, but is made by the effort produced by a reduced charge. There will, therefore, be a complete absence of that 90 bumping or violent impulse commonly experienced when a governor cuts in, particularly in engines of the Diesel or semi-Diesel type. The rod *a* is conveniently reciprocated from the engine crank shaft or 95 other moving part by means of the double armed lever *x* and the rod *y*.

The angle lever *f f'* may be operated against the action of its own spring and, as shown in the drawing, its arm *f'* may be 100 fitted with an adjustable set screw *q* for engaging the arm *g* of the cam plate spindle *h*, whereby the turning of the latter may be regulated to suit requirements. The arm *f* of the angle lever may be bent round and pointed at its extremity, as at *f*² so that it is fairly represented towards the direction of approach of the block *e* on the rod *a*, and is adapted for securely engaging with the annular recess *e'* in the forward end of such block *e*. It will be apparent that by withdrawing the set screw *p* in the trip lever *l' l''* to such an extent that it projects only one millimetre over the path of the rod *a* in the circumstances named, the delivery by 110 the pump on its first effective stroke after a resumption will be less than one third of the normal delivery. Therefore, the degree of adjustment of this set screw *p* determines the amount of the delivery by the pump during the first stroke after the governor 115 has cut in, as will be readily understood.

Referring to Figs. 4 and 5, 1 is the fuel pump, the piston of which is carried by a rod 2 connected to a member 3 on a rock-shaft 4, the piston being moved inwardly, against the action of a compression spring, by a tappet 5 fixed on the rock-shaft 6 by which the two-armed lever *x* is carried. 125 From the pump cylinder, the fuel is nor 130

1 mally pumped through a pipe 7 to the engine combustion chamber, this arrangement being well known.

- 2 *k* is the end or toe piece of the stem of a relief valve which is arranged in the pump casting and controls a by-pass passage communicating with the pump cylinder and also with the fuel supply thereto. While the engine is running normally the relief 10 valve closes the by-pass, so that fuel is supplied directly to the engine combustion chamber. When, however, the engine exceeds the desired speed and the disc *j* through the governor mechanism has been 15 rotated so that the toe piece *k* rests upon the larger diameter of the cam disc *j* the relief valve is thus raised and opens the by-pass passage between the pump cylinder and the fuel supply, so that the fuel instead of 20 being pumped into the engine is returned to the supply.

3 In an engine of two or more cylinders, it is important that the feed in each or all of the cylinders should be cut out simultaneously, otherwise one cylinder would be 25 colder than another and one would be more heavily loaded than another. In a suitable arrangement for a two cylinder engine, and as shown in Figure 2, one of the cylinders 30 is fitted with a mechanism such as is above described, all the similar parts in Figure 2 having the same reference letters as in Figure 1. The second cylinder is fitted with a cam plate or disc *j'*, like the first, for 35 operating on the fuel feed *k'* and the arm *g'* on the spindle *h'* of this cam plate *j'* is operated by the arm *g* of the other cam plate *j* by means of a slider *r* disposed between the two arms *g* and *g'*. The 40 trip pawl lever *s s'* of the second cam plate *j'* is adapted to be operated by a plunger *t* which, when the pawl *s* engages in a toothed recess *m'*, is projected by the trip lever *s'* into the path of a projection *x'* on the oscillatory two-armed lever *x* which drives the 45 reciprocal rod *a* aforesaid. As seen in Figure 2, a spring *u* is of sufficient strength to support the plunger rod *t* normally out of the way of the projection *x'*. When the 50 rod *r* is moved to the left however, thereby turning the arm *g'* and disc *j'*, the spring plunger *n'* lifts the pawl *s* into one of the recesses *m'* and depresses the arm *s'*, the latter pressing down the plunger *t* against 55 the action of the spring *u*. Thus the bottom end of the plunger *t* is projected into the path of the projection *x'* and the plunger is adapted to be raised and trip the lever *s'* at every outward movement of said projection.

60 Should however a high speed of the engine be maintained the cam-disc *j'* cannot turn, although the pawl *s* of the lever *s'* is disengaged therefrom, because the arm *g'*, fixed with relation to the disc *j'*, is re-

6 tained in the cut-out position by means of the slider *r*, which lies between the arms *g* and *g'* the former of which is locked by the pawl *l* engaging the disc *j*. When owing 70 to the reduction of engine speed, the cam disc *j* and its arm *g* are released, due to the tripping of the lever *l*, the return or cut in movement of the cam disc *j'* takes place directly the lever *s'* is tripped, through the plunger *t* being raised by the projection *x'*, the arm *g'* being then free to move to the right, as the slider *r* is no longer retained by the arm *g* of the cam disc *j*. Both cylinders will be cut out simultaneously and when normal speed is restored, the parts belonging to the first cylinder will first be 75 tripped and the valve *k* restored to the normal during the outward stroke of the rod *a* as above described, and the parts belonging to the second cylinder will then be tripped 80 and the valve *k'* restored during the following inward stroke of the rod *a*, that is to say by the projection *x'* striking the depressed plunger *t*, thereby achieving the objects of this modification.

85 The modification seen in Figure 3 is very similar to that illustrated in Figure 2, with the exception that the cam discs, such as *j j'* Figure 2, are dispensed with and arms *v v'* on the spindles *h h'* operate the stems 90 of the valve devices *k k'* through the medium of adjustable set screws *w w'*. Also in Figure 3, the arm *f'* of the lever *f f'* becomes a mere projection on the hub of this lever. This arm or projection *f'* strikes the lever arm *g* as before, and the arm *g* strikes a slider *r* which strikes an arm *g'* in the same manner as in Figure 2. In Figure 3, however, the arms *g g'* are lengthened and are fitted with projections or devices at *z z* 95 for engaging with the trip pawls *l* and *s* when the arms *g g'* are pushed over as described. The trip pawls *l* and *s* are raised to the operative position by the spring plungers *n n'* as in Figure 2, this raising of 100 the pawls bringing the adjustable set screw *p* on the arm *l'* into the range of movement of the rod *a* and causing the adjustable set screw *p'* on the arm *s'* to depress the plunger *t* so that the latter comes into the range of 105 movement of the projection *x'*. The operation of the mechanism seen in Figure 3, is, otherwise, similar to that of the mechanism seen in Figure 2.

110 All the above constructions have a further advantage which is gained during light running and may now be explained. In the ordinary way, and when an engine is running light, there is an explosion of a full charge, whereupon the governor cuts out 115 and the engine performs a large number of revolutions before the speed is sufficiently reduced for the governor to cut in again. Then takes place another explosion on a full charge, followed by a large number of idle 120

125 130

revolutions. Now with the mechanisms above described, when the governor cuts in, only a partial charge is supplied to the engine, so that, when running light, there will be a fewer number of idle revolutions before the governor cuts in again whereupon a further partial charge is supplied. Consequently, the proportion of effective revolutions to idle revolutions during light running is increased, so that the temperature of the engine is maintained and even running conditions are preserved.

I claim:—

1. An inertia governor for internal combustion engines, comprising a fuel cut-off device, means actuated by an excessive speed of the engine to operate said device to cut-off the fuel supply, and means operable during the return of the speed to normal to supply a subnormal charge of fuel to the engine.

2. An inertia governor device for internal combustion engines, comprising a fuel cut-out device, means actuated by an excessive speed of the engine to move said device into operative position for cutting out the fuel supply, an automatically operating device for retaining the cut-out device in its operative position, and adjustable abutment means on the retaining device adapted to be operated upon by the inertia device to release said retaining device when the speed of the engine returns to normal, said abutment device being adjustable to allow a subnormal fuel charge to be supplied to the engine, prior to the normal fuel feed being restored.

3. An inertia governor for internal combustion engines comprising fuel cut-off means, operating means adapted to shift said cut-off means to an operative position in which fuel supply is cut off from the engine, an inertia device normally moving clear of said operating means but adapted to engage said means during excessive speed, a trip detent adapted to engage and lock said cut-off means in the operative position, said trip detent in the engaged position being projected over the end of the normal path of releasing means moving with said inertia device, and automatic means constantly operative on said cut-off means in the direction for returning said cut-off means to the inoperative position.

4. An inertia governor for internal combustion engines comprising fuel cut-off means, operating means adapted to shift said cut-off means to an operative position in which fuel supply is cut off from the engine, an inertia device normally moving clear of said operating means but adapted to engage said means during excessive speed, a trip detent adapted to engage and lock said cut-off means in the operative position, an adjustable abutment on said trip detent, said abut-

ment being projected over the end of the normal path of releasing means moving with said inertia device, and automatic means constantly operative on said cut-off means in the direction for returning said cut-off means to the inoperative position.

5. An inertia governor for internal combustion engines comprising in combination fuel cut-off means automatically returnable to an inoperative position, operating means associated with said cut-off means, a governor rod reciprocated by the engine, an abutment on said rod adapted to engage said operating means when said rod is influenced by excessive speed, locking means associated with said cut-off means, and a two-armed detent having one arm adapted to operatively engage with said locking means when said cut-off means is shifted to the operative position, and the other arm adapted to overlap the end of the normal path of said rod when said engagement is effected.

6. An inertia governor for internal combustion engines comprising in combination fuel cut-off means automatically returnable to an inoperative position, operating means associated with said cut-off means, a governor rod reciprocated by the engine, an abutment on said rod adapted to engage said operating means when said rod is influenced by excessive speed, locking means associated with said cut-off means and adapted for locking the latter in the operative position, a two-armed detent having one arm adapted to operatively engage with said locking means when said cut-off means is shifted to the operative position, and an adjustable abutment on the second arm of said detent, said adjustable abutment being disposed so as to be projected over the end portion of the normal path of said rod when said locking engagement is effected.

7. An inertia governor for internal combustion engines with more than one cylinder, comprising a plurality of normally inoperative fuel cut-off means, one for each cylinder, operating means for one of said cut-off means and adapted to shift said cut-off means to an inoperative position, an inertia device normally movable clear of said operating means but adapted to engage said operating means during excessive speed, trip detents adapted to engage and lock said cut-off means in the operative position, said trip detents in the engaged position being projected over the end portions of the normal paths of respective releasing means moving with said inertia device, a transmission device arranged between two cut-off means for communicating movement received from the governor device by one of said means whereby all cut-off means of the plurality are operated in unison.

8. An inertia governor for internal combustion engines with more than one cylinder

- der, comprising a plurality of normally inoperative fuel cut-off means one for each cylinder, a plurality of control arms one for each cut-off means, a pivotal device in operative relation with one of said control arms, an inertia device normally movable clear of said pivotal device but adapted to engage the same under excessive speed conditions, transmission means adapted for communicating motion from one to another of said cut-off means, for effecting the operation of the latter in unison, a plurality of automatic locking detents appropriate to respective cut-off means, said detents being adapted to lock said cut-off means in the operative position, and release means driven by the engine and adapted for tripping said detents upon return of normal speed conditions, said release means being timed to effect said tripping late in the admission strokes of the respective cylinders for the purpose set forth.
9. An inertia governor arrangement for internal combustion engines comprising a plurality of normally inoperative fuel cut-off means one for each cylinder, a plurality of control arms one for each cut-off means, transmission devices disposed between said control arms for effecting the operation of said arms in unison, a pivotal device in operative relation with one of said control arms, an inertia device normally movable clear of said pivotal device but adapted to engage the same under excessive speed conditions, a locking detent for each cut-off means, said detents being adapted for automatically locking said cut-off means in the operative position, release arms on said detents, and striking devices adapted for operating said release arms when the latter have been shifted by the locking movements of said detents, said striking devices being driven by the engine and disposed so that they operate said release arms late in the inlet stroke of respective cylinders, for the purpose set forth.
10. An inertia governor arrangement for internal combustion engines comprising a fuel cut-off valve device, a cam device for operating said valve so as to produce either full or partial cut-off, an automatic detent for engaging and locking said cam in either of these positions, means constantly tending to turn said cam device to the inoperative position, a control arm associated with said cam device, a pivotal device in operative relation with said control arm, an inertia device normally moving free of said pivotal device but adapted for engaging same under excessive speed conditions, a release arm on said detent, an adjustable abutment on said release arm, and a striker operated by the engine and adapted upon a return of normal speed conditions to strike said release arm, while the detent engages the cam in the cut-off or partial cut-off position whereby the cam is permitted to return to the inoperative position in steps for the purpose set forth.

HENRY KENT-NORRIS.
